UNITED STATES PATENT OFFICE.

LOUIS LENGLLET, OF ST. LOUIS, MISSOURI.

LINING FOR FISH-CANS.

SPECIFICATION forming part of Letters Patent No. 232,517, dated September 21, 1880.

Application filed May 21, 1880. (No model.)

To all whom it may concern:

Be it known that I, LOUIS LENGLLET, of St. Louis, State of Missouri, have invented a new and useful Improvement in Linings for Cans to Preserve Shrimps and other Fish, of which the following is a specification.

The objects of my invention are to prevent the direct contact of the fish with the metal and solder of the can, and specially to provide the can with a lining the nature of which shall in no wise be injurious to the wholesomeness of the fish known as "lobsters," "shrimps," "clams," &c.

My invention can therefore be stated to consist in providing metal cans to contain shrimps and the like fish with corn-husk lining covering the inner surface of the can—that is to say, its annular sides and top and bottom—as will now more fully appear.

My improved lining is placed in the metal box illustrated in the accompanying drawings, in which—

Figure 1 is both a section and side elevation of a metal can which I prefer to use, and in which my lining is shown applied and ready for use. Fig. 2 is a plan section of Fig. 1. Fig. 3 is an enlarged detail section, showing the joint of the box projecting outside the cover, also showing part of the lining inside 30 of the box.

I apply and use my lining in metal cans preferably of the construction shown in the figures, and here briefly described as follows:

A is the annular body; B, the bottom; C, the cover. The lower and upper annular edges of the body A, bottom B, and cover C flange in the opposite directions, (shown by the letters $b' b' c' c'$), and the V-channel existing between the said flanges is closed by solder, as 40 plainly shown in Figs. 1 and 3. Such is the box or can which I prefer to employ, because the metal, where the joint of the bottom and cover is made to the body, does not project inside, also because the solder is on the outside; hence the contents are prevented from 45 injury arising from the oxidation of the metal, and which, as is well known, takes place when the fish are packed in cans having their cut edges of metal and solder joined on inside part 50 of the can.

My improved lining, which I provide inside the can, consists of the material known as "corn-husks," and is applied as follows: I se-

lect of the husks those blades that are the longest and broadest, cut the edges so that the 55 blade or leaf shall be of the proper size to fit the entire depth of the can from inside the cover to inside surface at bottom of the can. This done, the husk-leaf is placed inside the box or can and spread to be a cylindrical lining, e, 60 with its loose edges simply overlapping each other, as shown in Figs. 1 and 2. Two or more of the husk-leaves can be employed to duplicate the cylinder-lining e and add thickness to same, if desired. The opposite open 65 ends of the husk lining e, I close by disks $e' e^2$, made by cutting the like material into the disk shape of proper size to make the respective false cover and bottom, as shown more clearly in Figs. 1 and 2.

As apparent, the husk bottom e' and the cylindrical-shaped lining e are first placed in the can (the latter lining fitted to occupy the annular space contiguous to that of the body of the can, the former lining simply laid at the 75 bottom) before the fish are packed in the can. When the fish are stored in the can the upper disk-lining, e^2 , is placed on top of the fish, and, lastly, the metal cover is joined to the top to close the can.

I lay no claim to the metal can here shown and described.

I am also aware that cans have been provided with a wood lining; nor do I claim such.

The lining here employed, consisting of corn-husks, has the advantages of requiring no preliminary preparation to destroy or neutralize with acids any peculiar smell or essence of the material. In fact, I have discovered that the corn-husk is exempt from any odor that 90 can affect the taste or wholesomeness of the fish; also, that as a lining it keeps its natural and strong texture, is not expensive, is sufficiently thin as a layer, flexible, and as a material naturally adapted for the purposes to 95 line cans.

What I claim is—

In a metallic can for shrimps and the like fish, a lining consisting of corn-husks covering the inside annular body of the can, also its 100 top and bottom, as and for the purposes set forth.

LOUIS LENGLLET.
